By *W. S.* Attorneys,

Inventor
Sarah A. Ayerst.

C. Snow & Co.

UNITED STATES PATENT OFFICE.

SARAH A. AYERST, OF ABERDEEN, SOUTH DAKOTA.

HAT-STAND.

SPECIFICATION forming part of Letters Patent No. 533,422, dated February 5, 1895.

Application filed August 31, 1894. Serial No. 521,866. (No model.)

To all whom it may concern.

Be it known that I, SARAH A. AYERST, a citizen of the United States, residing at Aberdeen, in the county of Brown and State of 5 South Dakota, have invented a new and useful Hat-Stand, of which the following is a specification.

This invention relates to an improved device for supporting hats and other headgear 10 while on exhibition in shop windows and showcases, and it consists in certain peculiar features of construction, and combination and arrangement of parts whereby the efficiency of the arrangement is increased and a more 15 desirable article produced.

In the accompanying drawings: Figure 1 represents a perspective view of a hat stand constructed after the manner of my invention; Fig. 2, a sectional view, taken vertically 20 through the supporting arms; Fig. 3, a horizontal section taken through the plate for supporting the arms and looking downwardly therefrom.

The reference numeral 1 indicates the base 25 of my support, and this may be formed of either wood or metal, but preferably the former, and is provided with an upright or standard 2, to the upper end of which the plate 3 is secured by the screw 4, which passes down- 30 wardly into the standard 2. The plate 4 is elongated in one direction, and is formed with two openings 5 and 6 therein. The opening 5 is adapted for the reception of the rigid arm 7, which is secured therein by means of a pin 35 8, projecting horizontally through the plate 3 and through the lower end of the rigid arm 7, the lower end of said pin being extended beyond the plate and turned up to form a stud, having a hereinafter defined purpose.

From the plate 3 the rigid arm 7 extends 40 upwardly for a short distance, and truly vertically, after which it bends outwardly and extends off diagonally, as may be seen by reference to the drawings. Rigidly secured, by 45 riveting or otherwise, to the upper end of the arm 7, is the plate 9, which is bent or curved inwardly at its ends, so as to conform to the shape of the hat, as will be better explained hereinafter.

The opening 6 of the plate 3 is slightly elongated laterally, and provided for the recep-

tion of the swinging arm 10, of the support, which is passed through said opening and pivotally secured therein by the pin 11, passing horizontally through the plate and through 55 the arm. Owing to the elongated character of the opening 6, the arm 10 is capable of movement therein on its pivot 11.

The arm 10 is formed adjacent to the opening 6 with a straight portion *a*, which is connected at its upper extremity with an outwardly or diagonally extending portion *b*, corresponding to the outwardly-extending portion of the arm 7; while the lower end of the straight portion *a* is bent to form a short horizontally-extending part *c*. The extremity of the horizontal part *c* is notched at 12, and thereby connected to the retractile spiral spring 13, which extends upwardly from the arm and has its remaining end connected to 70 the stud formed by the pin 8. By these means the arm 10 is given an outward tendency at its upper end, which tendency is capable of being overcome upon the application of 75 more energy than is contained in the spring 13.

The upper end of the portion *b* of the arm 10 is provided with a plate 14, curved in conformity with the curvature of plate 9, and secured to the outer side of the arm, preferably by riveting.

In the use of my invention, the hat to be supported or exhibited is placed upon the upper ends of the arms 7 and 10, the said arm 10 being first moved on its pivot and against the tendency of spring 13. When the hat is 85 in place, the arm 10 should be allowed to assume its normal position, which will press the plates 9 and 14 against the respective sides of the hat and hold the same in place. The hat may be readily removed by swinging the 90 arm 10 as in the first instance, so as to disengage the plate of the arm 19 from the side of the hat.

The function of the plates 9 and 14 is to engage the hat and to steady the same, so as to 95 present a firm surface upon which the hat may bear.

Various changes in the form, proportion, and arrangement of the parts of my invention may be resorted to without departing from 100 the substance thereof. Therefore I desire it understood that I am not limited to the pre-

cise construction herein shown, but am entitled to all such variations as come within the above definition.

Having described the invention, I claim—
5 A hat support consisting of a supported plate having an elongated opening at one end, an arm passed through said opening and pivotally mounted therein, the upper end of the arm being projected upwardly and outwardly
10 and the lower end of the arm being projected downwardly and thence horizontally to a point vertically aligned with the side of the plate which is opposite the side having the elongated opening, a retractile spring con-

nected to the lower end of the arm and to the 15 plate at a point immediately above the said lower end and operating to throw the upper end outwardly, and a second arm rigid on the plate and projecting upwardly and outwardly therefrom so as to co-operate with the swing- 20 ing arm, substantially as described.

In testimony that I claim the foregoing as my own I have hereto affixed my signature in the presence of two witnesses.

SARAH A. AYERST.
